UNITED STATES PATENT OFFICE.

HANS HASS, OF BERGEDORF, NEAR HAMBURG, GERMANY.

GUIDING ARRANGEMENT FOR THE PROPELLER CURRENT OF SHIPS.

Application filed October 3, 1923. Serial No. 666,405.

To all whom it may concern:

Be it known that I, HANS HASS, a citizen of the German Republic, residing at Bergedorf, near Hamburg, Germany, have invented certain new and useful Improvements in a Guiding Arrangement for the Propeller Current of Ships, for which I have filed an application for patent in Germany on the 26th of February, 1923, and 10 of which the following is a specification.

By United States of America Patent No. 1,500,073 dated July 1st, 1924, it has already been proposed to give in single propeller ships to the hull or to the part of the same 15 in front of the propeller such a shape that the water flowing towards the propeller is deflected in a direction opposite the revolving direction of the propeller in order to increase in this manner the degree of efficiency 20 of the propeller.

This invention consists in transferring that idea to multiple-propeller ships and it relates to a special construction of the hull or of several parts of the same for this purpose.

The application of the invention to a twin-screw ship is illustrated by way of example on the accompanying drawing, wherein:—

Fig. 1 is a transverse section through a ship's hull along one of the last frames directly behind the propeller in viewing the port side of the ship.

Fig. 2 is an oblique section through the ship's hull on line II—II of Fig. 1, the propeller being shown in a slightly different position.

Fig. 3 is a longitudinal section through the ship's hull on line III—III of Fig. 2.

Fig. 4 is a similar view as Fig. 3 showing 40 however a somewhat modified construction.

Fig. 5 is a similar view as Fig. 3 showing 45 however another modified construction.

Fig. 6 is a transverse section similar to Fig. 1 but showing a modified construction.

Fig. 7 is a section on line VIII—VIII of 50 Fig. 6.

Fig. 8 is a section similar to that shown in Fig. 7 showing however a somewhat modified construction.

According to the invention each stern bracket or shaft housing 1 consists of a bearing portion and a web portion integral with the bearing portion and also integral with the adjacent plate covering the hull of the vessel. The web portion and the bearing 55 portion are arranged in the same plane ap-

proximately perpendicular to the inclined hull of the ship or in other words the web portions extend obliquely outwardly and downwardly as indicated in the drawing. 60 The upper surface of the web portion is bulged upwardly and arranged out of the common main plane of the web portion as shown at 2. This curved deflecting surface is inclined to the horizontal central plane 65 through the propeller axis with the rear edge turned in the direction opposite to the movement of the propeller in order to exert the desired guiding action on the water and pass it properly against the propeller blades, 70 the course of the direction of the water being indicated by directional lines 4 and 5 in Figs. 2 and 3.

In the form of construction shown in Fig. 4 the arm 6 of the stern bracket of the shaft 75 shows a specially pronounced curvature. In order to ensure notwithstanding this strong curvature a smooth flowing off of the water and to ensure the desired strong deflection of the same without disturbing 80 formation of eddies, for instance at the point 7, slits 8 are provided which extend from the pressure side to the suction side.

In the form of construction shown in Fig. 5 several deflecting surfaces are arranged the one behind the other, a stern bracket of the shaft with oblique arm 9 and at a short distance from the same a second oblique arm 10 extending between 85 the surface of the hull and the shaft bearing, the web portion of the bracket 11 surrounding the shaft merging into this arm 10. 90

According to Figs. 6 and 7 the arm 14 of the stern bracket of the shaft and the web portion of the bracket surrounding the 95 shaft are constructed as above described, but a correspondingly curved guiding surface 16 is besides arranged upon the other side of the propeller shaft and fitted on the web portion of the stern bracket of the shaft 100 in order to assist the effect of the curved web portion of said stern bracket.

In the form of construction shown in Fig. 8 several additional guiding surfaces are arranged at the side of the stern bracket of the shaft having an oblique arm 17 and a correspondingly extending web portion 18, in the form of construction shown by way of example for instance, two guiding surfaces 19 and 20. These additional guiding surfaces may extend over the entire diameter of the propeller or beyond the same. 110

In some cases a shorter length, as shown on the drawing, will however be sufficient.

Instead of two additional guiding surfaces a greater number of additional guiding surfaces may be arranged, if it should be necessary.

The special construction of the stern bracket of the shaft and of the web portion surrounding the shaft as described and 10 shown and the arrangement of the guiding surfaces may be conveniently used in any ship with any number of shafts.

I claim:—

1. An arrangement for guiding the propeller current of multiple-propeller ships, comprising a shaft housing uninterruptedly integral with the adjacent plates of the hull of the ship and including a bearing portion and a web portion, and curved surfaces on 15 the said web portion with the rear end turned in the direction opposed to the direction of the movement of the propeller blades, substantially as and for the purpose set forth.
- 20 2. An arrangement for guiding the propeller current of multiple-propeller ships, comprising a shaft housing uninterruptedly integral with the adjacent plates of the hull of the ship and including a bearing portion and web portion arranged in the same 25 general plane, curved surfaces on the said web portion with the rear end turned in the direction opposed to the direction of the movement of the propeller blades, and additional elongated guiding surfaces integral with the bearing portion of the said housing and curved to correspond to the said web faces, substantially as and for the purpose set forth.

3. An arrangement as claimed in claim 1, wherein slots are provided in the said web portion, substantially as and for the purpose set forth.

4. An arrangement as claimed in claim 1, wherein a plurality of elongated guiding surfaces are provided on the shaft housing.

In testimony whereof I affix my signature.

HANS HASS.
